UNITED STATES PATENT OFFICE.

JOSEPH T. JARET, OF BROOKLYN, NEW YORK, ASSIGNOR TO SUN-RAY LIGHTING PRODUCTS CO., INC., OF NEW YORK, N. Y., A CORPORATION OF NEW YORK.

DESIGN FOR A LAMP.

Application filed March 29, 1927. Serial No. 21,388. Term of patent 7 years.

To all whom it may concern:

Be it known that I, JOSEPH T. JARET, a citizen of the United States of America, and a resident of the city of New York, borough of Brooklyn, in the county of Kings and State of New York, have invented a new, original, and ornamental Design for Lamps, of which the following is a specification.

Reference is to be had to the accompanying drawing in which the figure is a perspective view of a lamp showing the new design.

I claim— The ornamental design for a lamp as shown.

JOSEPH T. JARET.
